1 Claim. (Cl. 287—189.36)

This invention is concerned with the building construction according to steel skeleton construction and the device for joining a corner of the skeleton of the building construction according to the steel skeleton construction.

The first object of this invention is to provide the building construction using the metallic member molded in Z section as a full web member.

The second object of this invention is to provide a device for joining a corner part of the skeleton of building construction using the metallic member folded in Z section as a full web member.

In the method for constructing buildings with steel skeleton construction various kinds of section steel are used, i.e. the web of the column and beam formed in a lattice the web of the column and beam formed in a plate, by hot rolling, or by automatic continuous welding process.

The present invention is concerned with a building construction using metallic Z section members (including a Z section member having ribs attached thereto) as a full web member thereof.

With this type of section, large sized frames or tapered ones can be simply formed by pressing iron plate. Thus, large scale equipment, such as is required for manufacturing H section members is not needed, and the cost of manufacturing is decreased. But Z section members are subjected to eccentric twisting stress due to the fact that the line of center of gravity of the Z section and the line of loading are not in coincidence. Besides the axial stress and bending stress in the direction of a common face of the column and beam are subjected to the stress in outward direction due to the fact that the principal axis of the section is inclined relative to the line of loading. Referring to the former, it can be solved by selecting the joint in such a way that the center of gravity line of the section is in coincidence with the line of loading, but in practical construction, some eccentric twisting can not be avoided.

The present invention is to balance the construction by combining a Z section member having section character as described above, in such a way that the whole skeleton construction does not have twisting in the same direction and deflection in the direction of the outside face. In steel skeleton construction, in the method for constructing a building in which members are to be assembled, the joining of the members plays an important part. If the joints are incomplete, the strength of whole building skeleton is lowered, and if the joints are complicated and difficult for assembly and cost of working is increased. It is therefore an object of the invention to provide for connecting the members in such way that: the various stresses acting at the joints are completely resisted; assembling and disassembling are eased; extra reinforcing members and special reinforced members are not needed; and special instruments and working process are not required.

The present invention is concerned with the apparatus for jointing the corner parts of a skeleton construction for a building using the full web section member of a metallic Z section member (including a Z section member with ribs).

2

Attached drawings show an example embodied according to this invention, in which,

FIG. 1 is a front view;

FIG. 2 is a plan view;

FIG. 3 is a perspective view;

FIG. 4 shows perspective views of disassembled parts of the joint part of the column and beam;

FIG. 5 shows perspective views of disassembled parts of the joint part of the beam;

FIG. 6 is a section through a column A taken along line VI—VI of FIG. 1; and

FIG. 7 is a section through a beam B taken along line VII—VII of FIG. 1.

Now, this invention will be explained referring to the attached drawings.

Column A and beam B are formed of metallic steel with a Z section having flanges 1, 2, 3 and 4 protruding in the opposite direction. The column and beam are overlapped and fastened in such a way that the outside flange 1 of column A and upper flange 3 of the beam B and the inner flange 2 and the lower flange 4 of the beam B are in opposing relationship to the web center line O—O of the Z section. The joint of column A and beam B and the joint of beams B, B are combined, overlapped and fixed in which a way that positions of each upper flange of beams and of each lower flange are in opposing relationship to the web center line O—O of the Z section.

The flanges 1, 2, 3 and 4 of column A and beam B are connected to the web overlapping each other and secured by the curved plates C and D applied respectively along the outside of the flanges 1 and 3 and the inner side of the flanges 2 and 4 of the corner. The fore ends of flanges 2 and 4 are attached with flanges 1 and 3 of the opponent member from inside by cover plates E and F.

The cover plates for the column and beam may be fastened by a suitable means such as bolt fixing (including high tension friction bolts), riveting and various kinds of welding such as plug welding etc.

According to the invention, each joint of a skeleton structure, namely in the joint of a column and beam of Z section or of a beam and beam of Z section, the outer flange of the column and the upper flange of the beam, the inner flange of the column and the lower flange of the beam, or the upper flange of beams, and the lower flange of the beams are placed on opposite sides relative to the web center line. Thus, even though twisting stress and an outward bending stress and deflection may occur in each member, the direction of stress and deflection at each node varies inversely, and in the whole a stabilized skeleton may be formed.

Such combined construction is used most typically, in the case of a gabled roof, with the left hand column and left hand beam, left hand beam and right hand beam, right hand beam and right hand column assembled as described above and, in case of an ordinary gate type skeleton, with the left hand column and beam, beam and right hand column assembled in the same way.

The inventive structure may be readily applied to multi-span and multi-floor buildings.

The invention may also be constituted, as described above, with Z section members which are longitudinally tapered.

Construction obtainable by combining such Z section members gives a good appearance.

As this invention is constituted as described above, from the point of view of resisting forces, firstly the web of the members are superposed resulting in having two times in thickness as a common web for the panel stress at the joint thereby insuring sufficient safety.

For flange stress, the stresses thereof can be transmitted by making the width and thickness of the cover plate applied along the outer and inner flange large enough.

Especially, in case of a Z section, the width of the cover plate becomes twice as large as the common flange width and is sufficiently strong. As the inner flange is engaged in overlapped parts, this serves as the stiffner for the panel parts.

From the point of view of construction, firstly there is no necessity for having additional reinforced ribs or stiffner and a cover plate of the web. Naturally since there is no special reinforced member, no special tool or process for assembling said joint are necessitated, and there is a room and space in which any means of bolting, riveting and welding can be used on the site.

Since rib stiffeners etc. are not attached to the end of the column and beam, the members may have the exact desired dimensions of the structure corresponding to the size of roof slope etc.

What I claim is:

In a building construction, a joint between two metallic members each having a Z section with first and second flanges protruding in opposite directions from a central web, said joint comprising the intersection of end portions of said two members in overlapping configuration with the webs of said members lying adjacent one another

10

15

and the flanges of said members lying in opposing relationship relative to the web center line of the adjacent members, and means to secure said members comprising four strap members each of which has a plurality of apertures therein, said apertures being in alignment with apertures in said flanges, a first strap member being secured to the first flange of both said first and second members, a second strap member being secured to said second flanges of both said first and second members, a third strap member being secured to the first flange of said first member and the second flange of said second member, and a fourth strap being secured to the second flange of said first member and the first flange of said second member.
